UNITED STATES PATENT OFFICE

ELEANOR P. SCHOLLE, OF NEW YORK, N. Y., ASSIGNOR TO ISABELLA BARCLAY, INC., OF NEW YORK, N. Y., A CORPORATION OF NEW YORK

DESIGN FOR A RADIATOR INCLOSURE

Application filed March 26, 1931. Serial No. 39,253. Term of patent 14 years.

To all whom it may concern:

Be it known that I, ELEANOR P. SCHOLLE, a citizen of the United States, residing at New York, in the county and State of New York, have invented a new, original, and ornamental Design for Radiator Inclosure, of which the following is a specification, reference being had to the accompanying drawings, forming a part hereof.

Figure 1 is a perspective view of a radiator

inclosure showing my new design, said view being lined to indicate the provision of mirrored surfaces at the front, top and sides, and

Figure 2 is a similar view showing the shutters of the inclosure in an open position.

I claim:

The ornamental design for a radiator inclosure as shown and described.

ELEANOR P. SCHOLLE.
